7 Claims. (Cl. 250—36)

This invention relates to a circuit for supplying electric oscillations to a load, said oscillations being generated or amplified by an oscillator or amplifier respectively comprising discharge tubes.

If such a circuit has to be in continuous use it is necessary to provide for a spare oscillator, or amplifier, which is put into service in the case of a disturbance of the oscillator or amplifier normally in use. Thus, for example, it is common practice in carrier-wave telephony systems comprising a plurality of speech channels to derive the carrier waves required for the various channels from a common carrier-wave generator, for example by frequency multiplication. In order to ensure that in the event of a disturbance in the said carrier-wave generator whereby the latter stops oscillating or only generates oscillations having a reduced amplitude the whole of the channels may not become unserviceable, provision must be made for a spare carrier-wave generator which comes into play automatically and thus permits the operation to proceed without interruption.

As an example of a circuit including an amplifier which has to be in continuous use, we may mention a telephone transmitting system comprising amplifiers included in a transmission line. In the case of a disturbance, for example due to one of the amplifier valves becoming defective, it is necessary for the defective amplifier to be replaced automatically by a reserve amplifier.

According to the invention, in a circuit arrangement including two oscillators or amplifiers comprising discharge tubes and a load in which the oscillator or amplifier from which the load is normally supplied is replaced by the other in the event of a disturbance, the two oscillators or amplifiers are so arranged that an at least transient variation of one of the operating voltages or one of the electric constants of one of the oscillators or amplifiers results in a sudden permanent change of its operating condition.

In order that the invention may be clearly understood and readily carried into effect it will now be described more fully with reference to the accompany drawings.

Figure 1 is a circuit arrangement of an oscillator embodying the invention.

Fig. 2 is a graph showing the relation between the amplitude of the oscillations generated in the circuit of Fig. 1 and the grid bias of the discharge tube thereof.

Fig. 3 is a schematic diagram of a circuit according to one embodiment of the invention.

Fig. 4 is a schematic diagram of a circuit according to a second embodiment of the invention,

Fig. 5 is a schematic diagram of a circuit which is a modification of the circuit arrangement shown in Fig. 1, and

Fig. 6 is a schematic diagram of a circuit according to another embodiment of the invention.

Fig. 1 shows a circuit arrangement of an oscillator comprising a backcoupled discharge tube 1.

10 The grid circuit of this tube includes an oscillatory circuit 2 which is coupled inductively to the anode circuit by means of a feedback coil 3. In addition, the cathode lead includes resistances 4 and 5 shunted by a condenser 6 which substantially forms a by-pass for the oscillations to be generated. These resistances are in series with a resistance 7 connected to the source of anode voltage 8 and so proportioned that the voltage drop brings about such a negative grid bias that the tube 1 is disrupted and the circuit does not oscillate. Connected in parallel with the resistance 5 is a switch 9 and a resistance 10 which is shunted by a condenser 11. When this switch 9 is closed the negative grid bias is reduced to such extent that the circuit starts oscillating. By correct adjustment of the circuit it may be ensured that the oscillations are maintained even after the switch 9 is reopened. If, however, the mutual conductance of the tube 1 decreases either 15 from age or by reduction of one of the supply voltages the circuit stops oscillating and the oscillations do not restart spontaneously even after the tube is renewed or the supply voltages have 20 reassumed their normal value.

25 In order that the operation described above may be clearly understood Fig. 2 shows the connection between the grid bias v_g of the tube 1 and the amplitude i of the generated oscillations. At low values of the grid bias no oscillations are 30 generated at all. If, however, the bias is increased to a value v_g' the circuit suddenly starts oscillating, the amplitude of the generated oscillations being i' . On further increase of the grid bias the amplitude of the generated oscillations 35 increases so as to give the curve ab . If the grid bias is then reduced the amplitude decreases so as to give the curve bc and at v_g'' suddenly jumps from the value i' to zero.

40 In the circuit shown in Fig. 1 with the switch 9 open the grid bias is adjusted to a value v_{g_0} comprised between $v_{g''}$ and v_g' at which oscillations do not start spontaneously. On the switch 9 being closed for a short time the grid bias is increased instantaneously to the value v_g' or higher 45 so that the switch tube starts oscillating. After

50 55

the switch 9 is reopened and the grid bias has therefore returned to the original value v_{g_0} the oscillations are maintained while having an amplitude i_0 . An increase of the mean direct current is incidental thereto.

If, however, due to a disturbance the voltage of the source 8 falls below a given value the oscillations cease and cannot restart again even after the voltage of the source 8 has reassumed its normal value. At the same time, the mean anode direct current decreases to zero. The same effect occurs if another operating voltage or one of the electric constants of the circuit decreases, for example if the mutual conductance of the tube decreases.

It follows from the above that the oscillator circuit is thus so arranged and adjusted that an at least transient variation of one of the operating voltages results in a sudden permanent change of the operating condition, that is to say that an inoperative oscillator is rendered operative after a transient increase of the grid voltage, whereas after a variation of one of the operating voltages or one of the electric constants resulting in a decrease of the amplitude of the oscillations generated the oscillator is rendered inoperative.

Fig. 3 shows two of such oscillators, similar reference numerals to those employed in Fig. 1 designating similar components; the components of the oscillator 13 shown on the right in the figure are distinguished by accents from those of the left hand oscillator 12.

The anode circuit of the oscillator 13 includes a relay 15 which is shunted by a condenser 14 and operates a switch 16. On this relay being energized by the anode current of the tube 1', the switch 16 connects to the right so that the load, which is connected to the terminals 18 and 19, receives energy from the oscillator 13 via a coil 17' coupled to coil 3'.

It is assumed that the oscillator 12 also generates oscillations but it cannot deliver energy to the load by this time. If, however, due to a disturbance the oscillator 13 is rendered inoperative in the manner described above with reference to Fig. 1 the relay 15 is de-energized due to the decrease of the mean anode-direct current, the switch 16 takes up the position shown and the oscillator 12 delivers energy to the load via the anode coil 3 and the coupling coil 17.

It follows that these oscillators are so connected that the variation of the mean anode-current caused by the cessation of oscillations in the oscillator initially supplying the load brings about the change of connections necessary to connect the load to the spare oscillator.

Fig. 4 shows a further embodiment of the invention. The circuit arrangement is substantially similar to that of Fig. 3, however the oscillator 12 has added to it a relay 20 which controls contacts 23, 25 and 26, a relay 21 which controls contacts 9, 9' and 27 and the relay 22 which controls contacts 15; and the oscillator 13 has a relay 15 which operates contacts 24 and 28. All contacts are shown in off position that is to say in the position in which the associated relay is not energised. In addition, the circuit includes two alarm circuits A and B, the alarm circuit A serving to give an alarm when the oscillator normally in use (the main oscillator) is thrown out of use and the connections are changed to the reserve oscillator, whereas the alarm circuit B serves to give an urgent alarm when both oscillators are rendered inoperative.

The oscillator 12 is the main oscillator, 13 is the reserve oscillator; both are in continuous use.

Since both oscillators operate the relays 20 and 5 15 are energised under the influence of the mean anode currents; the contacts 23 and 24 are closed, whereas the contacts 25, 26 and 28 are open.

Due to the contacts 26 and 28 being open the alarm circuit A is not in use. Relay 21 is energised due to the contacts 23 and 24 being closed; the contacts 9, 9' and 27 are consequently open; since contact 27 is open the urgent alarm circuit is also open.

15 Due to the relay 22 not being energised on account of contact 25 being open, contact 16 occupies the position shown and the load is coupled to the oscillator 12.

Thus, if one of the above-mentioned effects is 20 responsible for a disturbance in the oscillator 12 with the result that the latter is disrupted the energisation of relay 20 is suppressed due to the decrease of the mean anode current with the result that contacts 25 and 26 are closed and contact 23 is opened.

Thus, the following effect occurs: alarm is given due to the closure of 26; due to the closure of 30 25 the relay 22 is energised so that it changes the connections of contact 16 and couples the load to the oscillator 13. The opening of 23 has no further result.

In the event of oscillator 13 also being disrupted with the result that the energisation of relay 15 disappears the contact 24 is opened so that the energisation of 21 disappears, contact 27 is closed and urgent alarm is given in the circuit B.

Obviously, the same effect occurs when both oscillators are thrown out of use simultaneously, for example due to a disturbance in the common supply voltage.

Due to relay 21 being de-energised the contacts 9 and 9' are also closed and this results in the negative grid bias being so reduced that on 45 the return of the supply voltage both oscillators again become operative. This results in the relays 20 and 15 being re-energised and the contacts 9 and 9' being re-opened. Thus, the circuit arrangement of Fig. 3 ensures that if both oscillators are rendered inoperative due to the absence of at least one of the supply voltages a change of connections occurs under the influence of the mean anode currents of a discharge tube so that both oscillators are transformed into such 55 a condition that at least one delivers energy to the load upon the return of the missing supply voltage.

Properties similar to those possessed by the circuit of Fig. 1 can be obtained by means of the 60 circuit of Fig. 5, similar reference numerals to those employed in the previous figures again designating similar components. In this circuit arrangement the anode coil 3 is coupled to a coil 29 which supplies part of the output energy to a rectifier 30. The rectified voltage thus obtained, which is set up across a resistance 10, is used to decrease the negative grid bias which occurs across the resistances 4 and 5.

This circuit arrangement operates as follows: 65 The high negative bias which is set up across the resistances 4 and 5 prevents the tube 1 from generating oscillations. If the switch 9 is closed for a short time the operating point of the tube 1 is so displaced that oscillations are generated 70 and an alternating voltage is induced in the coil

29. This voltage is rectified by the rectifier 30 so that a compensating voltage is set up across the resistance 10 which displaces the operating point of tube 1 to such extent that oscillations are permanently generated. If, however, due to a disturbance, for example, the supply voltage falls below a given value the amplitude of the generated oscillations decreases, the compensating grid voltage across the resistance 10 decreases and the negative grid bias of the tube 1 is increased. Thus, the amplitude of the generated oscillations is again reduced and so forth so that eventually the tube is thrown out of operation.

In this circuit arrangement care should be taken that an increase of the grid bias does not result in an increase of the amplitude of the generated oscillations as otherwise the circuit would start oscillating at intervals, and this must be avoided. If this requirement is not satisfied, a stabilising element must be included in the circuit, for example a voltage limiter, such as a glow discharge lamp in parallel with the resistance 10.

The principle adopted in the oscillator circuit of Fig. 5 can also be employed with amplifiers.

Two cases have to be distinguished. In one case the oscillations to be amplified contain a component of constant value and frequency, such as occurs, for example, with amplifiers for carrier-wave telephony. In this case an alternating voltage of constant value can be derived from the output side of the amplifier and be supplied to a rectifier on the principle illustrated by Fig. 5. In the second case, in which there is no component that remains constant, such for example as with amplifiers for speech or music, the same effect may be obtained by means of an auxiliary oscillation lying outside the frequency band and supplied to the grid of one of the tubes, and this will be described more fully with reference to Fig. 6.

Fig. 6 shows a two-stage resistance-coupled amplifier in which in the manner mentioned before and by means of the component members 4, 5, 6, 7, 10 and 11 the tube 1 is given such a high negative bias that it is disrupted. The oscillations to be amplified, which are received for example via a telephone line, are fed, with the interposition of a low-frequency transformer 32, to the grid of tube 1 and in addition an auxiliary oscillation having a frequency lying outside the band to be amplified and a constant amplitude is transmitted to the said grid with the interposition of a transformer 33. The tube 50 is coupled to the anode circuit of tube 1 by means of the usual condenser 34 and resistance 35. The tube 50 receives a negative bias by way of a cathode resistance 36 shunted by a condenser 37.

To the output circuit of the tube 50 is connected for example a telephone line 38 with the interposition of an output transformer 39. The primary of the output transformer is shunted by a condenser 40. The output circuit also includes a circuit 41 tuned to the auxiliary oscillation; the oscillations that may occur in this circuit induce an alternating voltage in a coil 42 and this voltage is rectified by 30 so that a direct voltage is applied to the resistance 10.

For putting the circuit into service, the switch 9 is closed for a short time, the adjustment of the tube being normal, and both the oscillations fed by the transformer 32 and those fed by the transformer 33 are amplified by the arrangement. As a consequence of the direct voltage set up across the resistance 10 by the circuit 41, the coil 42 and the rectifier 30 the normal adjustment of the

tube 1 subsists even when the switch 9 is reopened. This circuit also may be embodied in a selective switching arrangement such as shown in Fig. 4.

5 In the circuit of Fig. 6 a disturbance such as a variation in the electric constants of the arrangement causing a decrease in the amplitude of the amplified oscillations, produces a corresponding decrease in the compensating voltage set up across the resistance 10. This decrease in voltage across resistance 10 makes the voltage applied to the control grid of the tube 1 more negative so that the tube is adjusted to a more unfavorable operating condition which in turn further reduces the amplitude of the amplified voltages. As a consequence of the cumulative action so produced, the circuit is automatically thrown out of operation.

10 Thus the circuits shown in Figs. 5 and 6 have the property that upon a transient decrease in the value of a grid voltage which normally blocks operation of the tube, oscillations are generated or amplified continuously. Furthermore, the generated or amplified oscillations provide a compensating voltage which at least partly suppresses the blocking voltage. Upon an at least transient change of one of the operating voltages or one of the electric constants of the circuit, the compensating voltage decreases in value thereby decreasing the amplitude of the generated or amplified oscillations which in turn further decreases the value of the compensating voltage. This action is cumulative and the oscillator or amplifier is rapidly rendered inoperative.

20 35 What I claim is:

1. A circuit arrangement for supplying electric oscillations to a load comprising, a circuit for normally supplying oscillations to the load including a discharge tube having a control electrode, a second circuit for supplying oscillations to the load upon failure of said first circuit and including a discharge tube having a control electrode, and means to connect said second circuit to the load upon failure of said first circuit, each of said 25 circuits including means associated with the control electrode of the discharge tube to produce a sudden and permanent change in the operating condition of the circuit upon the occurrence of an at least transient variation in the operating voltage or electric constants of the discharge tube.

2. A circuit arrangement for supplying electric oscillations to a load comprising a supply circuit

30 for normally supplying the oscillations to the load including an oscillatory circuit containing a discharge tube having a control electrode, a second supply circuit for supplying the oscillations to the load upon failure of said first circuit and including an oscillatory circuit containing a discharge tube having a control electrode, means to connect said second supply circuit to the load upon failure of said first supply circuit, each of said supply circuits including means associated with the control electrode of the discharge tube to produce a sudden and permanent change in the operating condition of the circuit upon the occurrence of an at least transient variation in the operating voltage or the electric constants of the circuit, said latter means including a circuit for applying to the control electrode a negative grid bias of a value at which an at least transient increase thereof will cause the continuous generation of oscillations and at which at least transient changes of one of the operating voltages or

of one of the electric constants of the circuit will make the supply circuit inoperative.

3. A circuit arrangement for supplying electric oscillations to a load comprising a circuit for normally supplying oscillations to the load including a discharge tube having a control electrode, a second circuit for supplying oscillations to the load upon failure of said first circuit and including a discharge tube having a control electrode, means to connect said second circuit to the load upon failure of said first circuit, each of said circuits including means to apply to an electrode of the discharge tube a blocking voltage sufficient to make the circuit inoperative, means to suppress said blocking voltage to thereby permit the continuous production of oscillations, and means controlled by the produced oscillations to obtain a compensating voltage which at least partly suppresses the blocking voltage and means controlled by an at least transient change in the operating voltage or one of the electric constants of the circuit to cause the compensating voltage to decrease so rapidly as to render the circuit inoperative.

4. A circuit arrangement for supplying electric oscillations to a load comprising a circuit for normally supplying oscillations to the load including a discharge tube having a control electrode, a second circuit for supplying oscillations to the load upon failure of said first circuit and including a discharge tube having a control electrode, means to connect said second circuit to the load upon failure of said first circuit, each of said circuits including means associated with the control electrode of the discharge tube to produce a sudden and permanent change in the operating condition of the circuit upon the occurrence of an at least transient variation in the operating voltage or electric constants of the discharge tube, and means controlled by variations in the mean anode current of the discharge tube of one of said circuits to connect the other circuit to the load when the first circuit becomes inoperative.

5. A circuit arrangement for supplying electric oscillations to a load comprising a circuit for normally supplying oscillations to the load including a discharge tube having a control electrode, and a supply voltage, a second circuit for supplying oscillations to the load upon failure of said first circuit and including a discharge tube having a control electrode, and a supply voltage, means to connect said second circuit to the load upon failure of said first circuit, each of said circuits including means associated with the control electrode of the discharge tube to produce a sudden and permanent change in the operating condition of the circuit upon the occurrence of an at least transient variation in the operating voltage or electric constants of the discharge tube, and means controlled by the mean anode current of one of the discharge tubes when both circuits are inoperative due to failure of at least

one of the supply voltages to place at least one of said circuits in condition to supply energy to the load when the supply voltage returns.

6. A circuit arrangement for supplying electric oscillations to a load comprising a supply circuit for normally supplying the oscillations to the load including an oscillatory circuit containing a discharge tube having a control electrode, a second supply circuit for supplying the oscillations to the load upon failure of said first circuit and including an oscillatory circuit containing a discharge tube having a control electrode, means to connect said second supply circuit to the load upon failure of said first supply circuit, each of said supply circuits including means associated with the control electrode of the discharge tube to produce a sudden and permanent change in the operating condition of the circuit upon the occurrence of an at least transient variation in the operating voltage or the electric constants of the circuit, said latter means including a circuit for applying to the control electrode a negative grid bias of a value at which an at least transient increase thereof will cause the continuous generation of oscillations and at which at least transient changes of one of the operating voltages or of one of the electric constants of the circuit will make the supply circuit inoperative, and means controlled by a change in mean anode current of the discharge tube of said first circuit to indicate when the circuit becomes inoperative.

7. A circuit arrangement for supplying electric oscillations to a load comprising a supply circuit for normally supplying the oscillations to the load including an oscillatory circuit containing a discharge tube having a control electrode, a second supply circuit for supplying the oscillations to the load upon failure of said first circuit and including an oscillatory circuit containing a discharge tube having a control electrode, means to connect said second supply circuit to the load upon failure of said first supply circuit, each of said supply circuits including means associated with the control electrode of the discharge tube to produce a sudden and permanent change in the operating condition of the circuit upon the occurrence of an at least transient variation in the operating voltage or the electric constants of the circuit, said latter means including a circuit for applying to the control electrode a negative grid bias of a value at which an at least transient increase thereof will cause the continuous generation of oscillations and at which at least transient changes of one of the operating voltages or of one of the electric constants of the circuit will make the supply circuit inoperative, and means controlled by the change in the mean anode currents of the discharge tubes of both circuits to indicate a disruption of both circuits.

GERARD HEPP.
